UNITED STATES PATENT OFFICE.

JOHN E. WRIGHT, OF NEW YORK, N. Y.

TELEGRAPH-TRANSMITTER.

SPECIFICATION forming part of Letters Patent No. 631,454, dated August 22, 1899.

Application filed May 5, 1899. Serial No. 715,702. (No model.)

To all whom it may concern:

Be it known that I, JOHN E. WRIGHT, a citizen of the United States, residing in the borough of Manhattan, in the city, county, and State of New York, have invented certain new and useful Improvements in Telegraph-Transmitters, of which the following is a specification, reference being had to the drawings accompanying and forming a part of the same.

The invention forming the subject of my present application for Letters Patent is a transmitter for printing or similar telegraphic instruments, the invention residing in certain improvements, hereinafter specifically pointed out, whereby the apparatus is rendered more durable and effective as a means for sending in rapid succession series of alternating-current impulses over a line for actuating a suitable receiver.

The apparatus as a whole is illustrated in the accompanying drawings, in which—

Figure 1 is a perspective view of the transmitter. Fig. 2 is a diagrammatic view illustrating in detail the construction and arrangement of the several parts of the apparatus.

The instrument is mounted on a suitable base A.

At the rear of the supporting-frame B are pivoted at *a* the key-levers C, the forward ends being beveled, as shown in Fig. 2, and resting normally on a bar D, which is carried by arms extending from a rock-shaft E. A spring *b*, connected with an arm *c* at one end and to the base A at the other, imparts to the bar a tendency to remain under the ends of the key-levers, and a spring-seated key or plunger F is employed to move the said bar forward or away from the key-levers by depressing an arm *d*, fixed to rock-shaft E.

Above the forward ends of the key-levers is the keyboard, in which are set the key-plungers G, which correspond to the various characters or operations which the receiver is capable of printing or performing. Each plunger straddles a corresponding key-lever, so that the depression of the one effects the depression of the forward end of the latter.

To the frame B, above the key-levers C, short levers H are pivoted at *e* and extend forward through notches in a bridge-bar K, secured to the frame B. Each lever H is connected

to the corresponding key-lever immediately under it by a link *i* and carries a spring-contact strip *g*, that projects forward and downward, as shown, terminating over a pin-barrel L. Spiral springs *f* are connected to the levers H or the fixed ends of the springs *g* and to the bridge-bar K, respectively, and act to maintain the levers H and C in an elevated position. The barrel L is mounted in suitable bearings at the sides of the frame B and carries a series of pins *h*, set in its metallic surface in a spiral line. Rotation is imparted to the barrel by a spirally-toothed wheel M, fixed to the end of the shaft and meshing with a worm N on a shaft O, mounted in bearings on the base of the instrument. On the shaft O is a pulley P, held to the shaft by friction and adapted to be driven by a belt from a suitable motor.

The shaft O carries at its forward end a commutator composed of a hard-rubber cylinder *n*, in the surface of which are set the continuous metal rings *o p* and the four plates *r s t v*. A plate R, of insulating material, is secured to the base A and to it are secured four spring-contact strips S S and T T, which bear on the surface of the commutator in position to make contact with the plates thereon, respectively.

A collar with two diametrically-opposite projections or studs *x* is secured to the shaft O by a set-screw. In the plane of rotation of the studs *x* there is pivoted an armature-lever *y*, having a hinged extension *z*. A spring V, connected to the lever *y*, holds the latter away from the poles of its magnet W, while a spring *u*, connected with the hinged extension *z*, holds the latter down upon an adjustable stop *j*.

The apparatus as thus constructed is used and operated in the following manner: The shaft O is set in rotation by a motor, which is not shown in the drawings, and as the magnet W is normally inactive its armature is held out of the path of the studs *x*. At the same time all of the key-levers are raised and none of the spring-contacts *g* is in engagement with a pin on the barrel L. As long as the shaft O rotates the commutator sends alternately opposite current impulses over the line I from the main battery J. This may be done by any suitable arrangement of the cir-

cuit connections—as, for example, the two poles of the battery J are connected to the springs or brushes S S, the ring o is in electrical connection with plate s and plate t, while ring p is connected to plate v and plate r, as indicated in dotted lines. By each revolution of the commutator therefore a positive and a negative impulse will be sent over the line. If any key, as F, be depressed, the 5 beveled end of the lever C, which is operated by it, forces forward the bar D, which, returning to position as soon as the key passes below it, locks the key down, as indicated in Fig. 2. The depression of the key-levers 10 brings down the end of the spring-contact g into the path of its corresponding pin h, and at the instant of contact between the two the local circuit m of the magnet W is closed, as one end of this circuit is connected to the 15 levers, while the other is connected to the insulated metallic surface of the drum L by a brush l. When the magnet W becomes energized, it draws down the lever y, tilting the extension z, so that the end of the latter 20 lies in the path of the studs x. The shaft O will in consequence be arrested as soon as either of the studs engages the end of the extension z, and a prolonged current impulse 25 will in consequence be sent to line. If now 30 another key be depressed, it forces the bar D forward, which releases the key previously locked down, but is itself locked until released either by another key or by the special key F. The release of the first key, however, 35 breaks the circuit of magnet W and this permits the commutator to revolve, sending alternating impulses to line until the pin corresponding to the second key depressed engages with the spring-contact g, when the 40 barrel is again arrested. There are, say, thirty-two pins on the barrel and the latter makes one revolution for every sixteen revolutions of the shaft O. Hence from the arrangement of contacts on the commutator 45 there will be thirty-two impulses sent to line for each complete revolution of the barrel L. The number of impulses, sent therefore, between the depression of any two keys will correspond exactly to the distance in arc between the pins corresponding to such keys or 50 to the number of pins comprised in such arc.

The special object in view in the features of the apparatus which embody my improvement will now more readily appear. The pin-barrel is positively stopped the instant that 55

the rotation of the shaft O is arrested and the tendency to a retrograde movement due to shock is entirely avoided. Moreover, since the pin-barrel is not arrested by the mechanical engagement of the pins and keys no injury is done to either of the latter. The pins are advantageously beveled at their ends and the spring-contacts bent downward, so that a long rubbing contact is insured. 60

Having now described my invention, what I claim is— 65

1. In a telegraph-transmitter, the combination with a pin-barrel connected with one terminal of a local circuit, a series of keys having contacts adapted to engage with the pins 70 when depressed and connected with the opposite terminal of the circuit, means for imparting rotation to the pin-barrel, and a locking device controlled by the local circuit and adapted to arrest the pin-barrel when any pin 75 and its corresponding key-contact are brought into engagement, as set forth.

2. In a telegraph-transmitter, the combination with a pin-barrel and its driving mechanism, of a series of keys, an electric circuit 80 adapted to be closed by the contact of any key with its corresponding pin, and means controlled by said circuit for locking and releasing the said driving mechanism, as set forth.

3. In a telegraph-transmitter, the combination with a pin-barrel, of a driving-shaft imparting rotation to the barrel through a worm-gear, a series of keys, an electric circuit adapted to be closed by the contact of any key with its corresponding pin, a locking device for arresting the rotation of the driving-shaft, and an electromagnet in the key-controlled circuit for operating the said locking device, as set 85 forth. 90

4. In a telegraph-transmitter, the combination with a pin-barrel, a shaft imparting rotation to the barrel through suitable gearing, a commutator carried by said shaft for sending current impulses to line, a locking device adapted to encounter studs or stops on the 100 shaft, a series of keys, an electric circuit adapted to be closed by the engagement of any key with its corresponding pin, and an electromagnet in said circuit for controlling the operation of the locking device, as set 105 forth. 95
